ESTERS OF PIPERAZINE 1,4-DIETHANOL
 Gianfranco Pala, Milan, Italy, assignor to Istituto de
 Angeli S.p.A., Milan, Italy, a corporation of Italy
 No Drawing. Filed Nov. 20, 1964, Ser. No. 412,859
 Claims priority, application Great Britain, Apr. 28, 1964,
 17,604/64
 4 Claims. (Cl. 260—268)

This invention relates to new N,N'-di(β-hydroxyethyl) piperazine esters of α-substituted 1-naphthyl-acetic acids.

According to the invention, I provide compounds of the general formula

(in which R represents a hydrogen atom or straight-chained alkyl group containing 1 to 5 carbon atoms)

5

10

15

20

2

Particularly preferred for their spasmolytic activity are the free bases and acid addition salts in which R represents a hydrogen atom or a methyl or ethyl group. Pharmacological tests have been carried out to illustrate the spasmolytic activity of the α-methyl-1-naphthylacetic acid diester of N,N'-di(β-hydroxyethyl)-piperazine (hereinafter designated DA-914). The results of the tests are as follows:

Spasmolytic activity on guinea-pig ileum "in vitro"

The test was carried out in segments of guinea-pig ileum according to the Magnus-Technique. The intestine was stimulated with standard doses of acetylcholine (1.10⁻⁷ g./ml.), histamine (1.10⁻⁶ g./ml.), BaCl₂ (1.10⁻⁴ g./ml.), nicotine (2.10⁻⁶ g./ml.) and serotonin (1.10⁻⁶ g./ml.), and then the dosage of the substances able to produce a 50% inhibition of the contractions was determined. In the following table are stated the ED₅₀ values of DA-914 and also (for comparison purposes) of typical inhibitors for the contracting agents used, calculated according to the method of M. F. Lockett and coll. (J. Pharm. and Pharmacol., 8, 18, 1956).

	Acetylcholine, ED ₅₀ , g./ml.	BaCl ₂ , ED ₅₀ , g./ml.	Histamine, ED ₅₀ , g./ml.	Nicotine, ED ₅₀ , g./ml.	Serotonin, ED ₅₀ , g./ml.
DA-914.....	3.9.10 ⁻⁸	3.9.10 ⁻⁸	4.10 ⁻⁸	3.7.10 ⁻⁸	4.1.10 ⁻⁸
Diphenhydramine hydrochloride.....			8.3.10 ⁻⁹		
Papaverine hydrochloride.....		5.1.10 ⁻⁶			
Atropine sulphate.....	5.510 ⁻⁹				
Hexamethonium bitartrate.....				12.6.10 ⁻⁷	

and mono- and di-acid addition salts thereof, the anions associated with said salts being physiologically acceptable at the effective dosage of the compounds.

The compounds according to the invention possess particularly valuable spasmolytic activity of the myolytic type which is generally more pronounced than that of known compounds of related structure. The spasmolytic activity may be demonstrated in vitro on segments of guinea-pig ileum stimulated by barium chloride, acetyl choline and histamine. The compounds according to the invention also have relatively low toxicity, and for example the LD₅₀ in mice of the dihydrochloride of the α-methyl-1-naphthyl acetic acid diester of N,N'-di(β-hydroxyethyl)-piperazine by the intraperitoneal and oral routes respectively is 331 mg./kg. and >1600 mg./kg., while chronic toxicity tests showed that rats could tolerate 50 mg./kg. of the above hydrochloride without noticeable effect on growth-curves or effects on the organs detectable by histological examination.

The compounds according to the invention are colourless crystalline solids. The free bases are insoluble in water and soluble in alcohol whilst the acid addition salts are sparingly soluble in alcohol and very moderately soluble in water. Particularly preferred compounds according to the invention, by virtue of their high spasmolytic activity, are those compounds of Formula I in which R represents a lower alkyl group containing 1 to 3 carbon atoms. The salts according to the invention may be formed by treating the free base with an acid, for example a hydrohalic acid such as hydrochloric or hydrobromic acid, phosphoric acid, sulphuric acid, methane sulphonic acid or methane-disulphonic acid. It will be appreciated that where R is other than hydrogen the compounds possess asymmetric carbon atoms and may exist in optically active or racemic forms all of which forms are comprised within the present invention. In such compounds, two asymmetric carbon atoms are present and the compounds may also be in the meso-form.

35

40

45

55

60

65

As can be seen from these results, DA-914 is 203 times more active than papaverine and 42 times more active than hexamethonium bitartrate.

Spasmolytic activity on guinea-pig ileum "in vivo"

The test was carried out according to the method of Brock and coll. (Arch. Exp. Path. Pharmacol., 215, 512, 1952), modified by Setnikar (J. Pharmac. Exp. Ther., 130, 356, 1960). The contractions were produced, every 4 minutes, by perfusion of the peritoneum with BaCl₂ solution at the concentration of 10 mg./l. The perfusion was of 30 seconds duration and the intestinal movements were recorded by means of a water manometer. The compound to be tested was injected, intravenously, at various dosage levels 75 seconds prior to the perfusion. As a means of comparison it was preferred to administer ethaverine hydrochloride rather than papaverine because of the former's lower toxicity. The dose inhibiting to a 50% degree the contractions produced by BaCl₂ was calculated as in the previously described in vitro test. The results are given in the following table:

	Dose, mg./kg./i.v.	Percent inhibition of contraction stimulated by BaCl ₂	ED ₅₀ , mg./kg.
DA-914.....	5	36	6.7
	7.5	54	
	10	72	
Ethaverine hydrochloride.....	5	25	10.3
	10	47	
	20	75	

Spasmolytic activity on rat uterus "in vitro"

The rat uterus was prepared according to the method described by Burn (Biological Standardisation, Oxford University Press, London, 1950 (page 177). The organ was stimulated, every 3 minutes, with oxytocine and BaCl₂ at the final concentration of 2.10⁻⁸ I.U./ml. and 1.10⁻⁴

g./ml., respectively. The substance under examination was added to the nutrient solution every 2 minutes prior to the stimulation. In the following table are stated the ED₅₀ values calculated according to the method used in the above-described test carried out in the guinea-pig ileum "in vitro."

	Oxytocine, ED ₅₀ , mg./ml.	BaCl ₂ , ED ₅₀ , mg./ml.
DA-914	1.9.10 ⁻⁸	2.0.10 ⁻⁸
Papaverine hydrochloride	1.1.10 ⁻⁸	9.8.10 ⁻⁷

According to a still further feature of the invention, I provide compositions comprising one or more compounds according to the invention in association with a pharmaceutical carrier or excipient.

The compositions according to the invention may be adapted for oral, rectal or parenteral administration, advantageously in the form of dosage units, each dosage unit being adapted to supply a single dose of active ingredient. The dosage units of the compositions according to the invention may for example take the form of tablets, dragees, capsules, suppositories or ampoules. Other convenient forms of compositions according to the invention include suspensions, syrups, etc. The pharmaceutical carriers or excipients in the compositions may for example be those conventional in the art, for example tabletting excipients, capsule gelatin, suppository bases, water, edible oils, flavouring, sweetening, odour-producing, suspending, dispersing or thickening agents and the like.

The free bases and acid addition salts according to the invention are preferably present in the dosage unit preparations in quantities of from 1 to 200 mg., advantageously 10 to 100 mg., per dosage unit.

The free bases of Formula I provided by the present invention are insoluble in water whilst acid addition salts thereof, such as the hydrochloride, hydrobromide, sulphate and phosphate acid addition salts, are only very moderately soluble in water yielding aqueous solutions with low pH, for example of from 2 to 3. This is advantageous where pharmaceutical compositions in the form of, for example, injectable solutions are to be prepared. One advantageous form of compositions according to the invention comprises, therefore, one or more compounds according to the invention together with a solubility promoter. Such compositions according to the invention may, for example be in the form of a solid mixture suitable for addition to distilled water to form an injectable solution or in the form of the injectable solution itself.

Solubility promoters are compounds which have the effect of increasing the solubility in water of sparingly soluble compounds and are in general well-known in the art. One class of compounds which may conveniently be used as solubility promoters are compounds having a

group, especially amides and derivatives thereof. Among the solubility promoters of this class which may be used in accordance with the invention are included metamizole (sodium - 1 - phenyl - 2,3 - dimethyl - 5 - pyrazolone - 4 - methylaminomethane sulphonate), urea, nicotinamide, nicotinamide ascorbate, piperazine, urotropine (hexamethylene-tetramine), antipyrene, acetamide, dimethylacetamide and coramine. Particularly useful solubility promoters of this class include metamizole, nicotinamide and acetamide. A second class of compounds which may conveniently be used as solubility promoters are compounds having a $-\text{O}-\text{CH}_2-\text{CH}(\text{OH})-\text{CH}_2\text{OH}$ group, especially 3-(substituted phenoxy)-1,2-propanediols. Examples of compounds of this class include

3-(2-methoxy-phenoxy)-1,2-propanediol,
3-(2-methoxy-4-propionyl-phenoxy)-1,2-propanediol,
3-(2-methyl-4-propionyl-phenoxy)-1,2-propanediol, and
3-(2-chloro-4-propionyl-phenoxy)-1,2-propanediol.

Particularly useful compounds of this class are 3-(2-methoxy-phenoxy)-1,2-propanediol and 3-(2-methoxy-4-propionyl-phenoxy)-1,2-propanediol. Injectable solutions prepared in this way in general have sufficient thermal stability to withstand the necessary sterilisation, whilst dilution of the solutions may result in the precipitation of the compounds according to the invention in an insoluble form.

The use of solubility promoters may, according to the nature of the solubility promoters, also result in an increase in the pH of injectable solutions. Thus, the α -methyl-naphthylacetic acid diester of N,N'-di-(β -hydroxyethyl)-piperazine dihydrochloride has a solubility of 0.5% by weight yielding an aqueous solution having a pH of about 2.5, whilst the use of metamizole as solubility promoter makes possible the preparation of aqueous solutions containing 5% by weight of the diester and having a pH of about 5.5.

Injectable solutions according to the invention containing solubility promoters may for example be prepared by addition of one or more compounds according to the invention (preferably in the form of acid addition salts e.g. dihydrochlorides) to an aqueous solution containing the solubility promoter. The addition may be effected for example at room temperature with continuous stirring. The solubility promoter is generally used in excess, for example four to fifty times the weight of the compound according to the invention.

The compounds according to the invention may be prepared by any convenient method, for example by reaction of a piperazine derivative of the formula

35 with a 1-naphthylacetic acid derivative of the formula

40 45 (the group R being as defined above and X and Y representing groups able to react together to form divalent $-\text{O}-\text{CH}_2-\text{CH}_2-$ radicals) and, if desired, conversion 50 of the compound of Formula I thereby obtained into a mono- or di-acid addition salt thereof.

The compounds are particularly advantageously prepared by any one of the following processes which constitute further features of the invention.

55 (A) An acid halide, preferably the chloride, of an α -substituted or unsubstituted 1-naphthyl acetic acid is reacted with N,N'-di-(β -hydroxyethyl)-piperazine. The reaction is preferably carried out in the presence of an acid-binding agent, such as an inorganic base, e.g. sodium 60 or potassium carbonate or bicarbonate, or a tertiary amine such as pyridine, dimethylaniline, N-methylmorpholine etc., advantageously under substantially anhydrous conditions in an inert solvent medium. Examples of suitable solvents which may be used are hydrocarbon 65 solvents such as benzene, xylene or toluene, ethers such as diethyl ether or dioxan, and inert liquid nitriles such as acetonitrile. The reaction is conveniently effected under reflux at the boiling point of the solvent. The acid halides of the 1-naphthyl acetic acids used as starting materials 70 are conveniently prepared by reacting the free acid with a halogenating agent, such as, e.g. thionyl chloride or phosphorus oxychloride. The preparation of various mono- α -substituted 1-naphthyl acetic acids is described 75 in our copending application No. 6,772/62.

(B) A β -haloethyl ester, preferably the β -chloroethyl ester of an α -substituted or unsubstituted 1-naphthyl acetic acid is reacted with piperazine advantageously in the presence of a solvent. An acid-binding agent may conveniently be present for example an inorganic base, such as an alkali or alkaline earth metal hydroxide, carbonate or bicarbonate, e.g. sodium bicarbonate or potassium or calcium carbonate. Suitable solvents which may be used include, for example, hydrocarbon solvents such as benzene or toluene, alcohols such as ethanol or methanol and ethers. The reaction is conveniently carried out under reflux at the boiling point of the solvent.

(C) Transesterification of esters, preferably alkyl esters of α -substituted or unsubstituted 1-naphthyl acetic acids with N,N'-di-(β -hydroxyethyl) piperazine, preferably in the presence of a transesterification catalyst such as an alkali metal hydroxide, amide etc. or strong organic or inorganic acids, e.g. sodium hydroxide or amide, p-toluenesulphonic acid or sulphuric acid. The reaction is preferably carried out under substantially anhydrous conditions in a solvent medium, such as, for example, a hydrocarbon solvent e.g. benzene or toluene. The alcohol which is formed during the reaction is preferably removed by distillation. The esters of the α -substituted or unsubstituted 1-naphthyl acetic acids are conveniently prepared from the free acids by conventional methods of esterification.

(D) An alkali metal salt, preferably the sodium salt, of an α -substituted or unsubstituted 1-naphthyl acetic acid is reacted with an N,N'-di-(β -haloethyl) piperazine, preferably N,N'-di-(β -chloroethyl) piperazine, advantageously in the presence of a solvent medium such as, for example, an alcohol e.g. methanol, ethanol or iso-propanol, a hydrocarbon solvent such as benzene or toluene or an ether such as diethyl ether or dioxane.

For the better understanding of the invention, the following examples are given by way of illustration only:

EXAMPLE 1

(a) Preparation of acid chlorides of α -substituted-1-naphthyl acetic acids.—15 g. of α -methyl-1-naphthylacetic acid were refluxed with 50 ml. of thionyl chloride during 3 hours. The excess thionyl chloride was removed under reduced pressure and the product was also isolated by distillation under reduced pressure. Yield: 15.6 g. (96%). The α -methyl-1-naphthyl acetyl chloride boils at 120–124° C./0.1 mm.

The following acid chlorides were also prepared by this method:

TABLE I

R	Empirical formula	B.P., ° C.	Yield (percent)
H	C ₁₂ H ₉ OCl	175–176/15 mm	95
C ₂ H ₅	C ₁₄ H ₁₃ OCl	130–135/1 mm	98
n-C ₃ H ₇	C ₁₅ H ₁₅ OCl	132–135/0.5 mm	93
n-C ₄ H ₉	C ₁₆ H ₁₇ OCl	143–147/0.55 mm	99

(b) 3.52 g. of N,N'-di-(β -hydroxyethyl)-piperazine, 2.8 g. of sodium bicarbonate and 8.90 g. of α -methyl-1-naphthyl acetyl chloride were refluxed with stirring during 5 hours in 60 ml. of anhydrous benzene. After cooling the

75

mixture was filtered and the benzene evaporated off under reduced pressure.

10.5 g. of crude ester were obtained. The hydrochloride was prepared by dissolving the ester in absolute ethanol and treating the solution with anhydrous gaseous hydrogen chloride. 10.75 g. of hydrochloride were obtained. Yield 85%. M.P. 220–221° C.

Analysis for C₃₄H₃₈N₂O₄·2HCl. Found: C, 66.65%; H, 6.52%; N, 4.63%. Calc.: C, 66.76%; H, 6.59%; N, 4.58%.

EXAMPLE 2

1.76 g. of N,N'-di-(β -hydroxyethyl)-piperazine, 1.9 g. of sodium bicarbonate and 4.45 g. of α -methyl-1-naphthylacetyl chloride in 30 ml. of anhydrous acetonitrile were refluxed with stirring during 5 hours.

After cooling the mixture was filtered and the acetonitrile evaporated off under reduced pressure. 5.2 g. of crude ester were obtained. The ester was converted into the hydrochloride by the method described in Example 1. Yield 5.21 g. (84%), M.P. 220–221° C.

EXAMPLE 3

18.5 g. of α -propyl-1-naphthylacetic acid, 100 ml. of methyl alcohol and 3 ml. of concentrated sulphuric acid were refluxed during 3 hours. After cooling the solution was concentrated under reduced pressure, poured into water and extracted with ether. Upon distillation under reduced pressure 14.45 g. of α -propyl-1-naphthylacetic acid methyl ester were obtained, boiling at 133–135° C./0.8 mm.

7.05 g. of α -propyl-1-naphthylacetic acid methyl ester, 2.5 g. of N,N'-di-(β -hydroxyethyl)-piperazine, 1 g. of sodium amide and 45 ml. of anhydrous benzene were reacted in a distillation apparatus provided with a reflux condenser. Methyl alcohol was removed by distillation and, simultaneously, a further 25 ml. of anhydrous benzene were added. The solution was cooled after 4 hours, decomposed with iced water and extracted with ether. After evaporation of the solvent, 7 g. of crude ester were obtained which was converted into the hydrochloride as described in Example 1. Yield 6.88 g. (72% calculated on the methyl ester). M.P. 213–214° C.

EXAMPLE 4

4.44 g. of sodium α -methyl-1-naphthyl acetate, 2.14 g. of N,N'-di-(β -chloroethyl)-piperazine in 50 ml. of iso-propanol were refluxed during 48 hours. The mixture was cooled, filtered and the isopropanol evaporated. 5.23 g. of crude ester were obtained, which was converted into the hydrochloride by the method described in Example 1. Yield 3.35 g. (55%). M.P. 220–221° C.

EXAMPLE 5

10 ml. of pyridine were added dropwise during 10 minutes into a solution of 10 g. α -propyl-1-naphthylacetyl chloride and 3.5 g. of ethylene chlorohydrin in 50 ml. of anhydrous benzene. The reaction mixture was refluxed with stirring during 3 hours. After cooling, the mixture was filtered and the benzene evaporated off under reduced pressure. The residue was distilled under reduced pressure. 8 g. of α -propyl-1-naphthylacetic acid β -chloroethyl ester were obtained, boiling at 165–168° C./0.9 mm. 5.8 g. of α -propyl-1-naphthylacetic acid β -chloroethyl ester, 1.9 g. of piperazine hydroxide and 1.7 g. of sodium bicarbonate in 20 ml. of ethyl alcohol were refluxed during 24 hours. The mixture was cooled, filtered and the alcohol evaporated off. The residue was taken up in ether, the ethereal solution filtered and the ether evaporated off. 6 g. of crude ester were obtained, which was converted into the hydrochloride as described in Example 1. Yield 3.35 g. (50%, calculated on the β -chloroethyl ester), M.P. 213–214° C.

The following compounds of general Formula I were also prepared by the method of Example 1.

R in Formula I	Empirical Formula	Yield, Percent	M.P., °C.	Analysis			
					C Percent	H Percent	N Percent

EXAMPLE 6

Tablets: Formulation for the preparation of 1000 units.

α -Methyl-1-naphthylacetic acid diester of N,N'-di-(β -hydroxyethyl)-piperazine dihydrochloride	25

Lactose	150

Corn starch	23

Magnesium stearate	2

Preparation: The active substance, excipients and half of the magnesium stearate are intimately mixed. The homogeneous mixture is then formed into pellets which are granulated. The remaining magnesium stearate is added to the granulate and pressed into convex tablets weighing 200 mg. Each tablet contains 25 mg. of active substance.

EXAMPLE 7

Dragees: Formulation for the preparation of 1000 units.

α -Ethyl-1-naphthylacetic acid diester of N,N'-di-(β -hydroxyethyl)-piperazine dihydrochloride	25

Lactose	100

Corn starch	23

Magnesium stearate	2

Sucrose	150

Gum-arabic, colour, distilled water, q.s.	

Preparation: Prepare convex tablets as described in the previous example weighing 150 mg. The obtained tablets are then covered with sucrose syrup, gum-arabic and colour until reaching the weight of 300 mg. Each dragee contains 25 mg. of active substance.

EXAMPLE 8

Syrup: Formulation for the preparation of 1 litre.

α -Methyl-1-naphthylacetic acid diester of N,N'-di-(β -hydroxyethyl)-piperazine dihydrochloride	5

Gum tragacanth	5

Polyoxyethylene sorbitan monolaurate	5

Flavour and colour, q.s.	

Sucrose syrup at 50%, q.s. for 1 litre.	

Preparation: The ingredients are dissolved at a temperature of 40° to 50° C. After cooling the solution is adjusted to the required volume. Each teaspoonful (5 ml.) contains 25 mg. of active substance.

EXAMPLE 9

Suppositories

Formulations for the preparation of 1000 suppositories:

	A, g.	B, g.
α -Methyl-1-naphthylacetic acid diester of N,N'-di-(β -hydroxyethyl)-piperazine dihydrochloride	25	50
Cocoa butter (or glycerides of saturated fatty acids, q.s. to	2	2

The well crushed active substance is incorporated into the melted excipient. The homogeneous mixture is filled

into moulds and allowed to cool. Each suppository contains 0.050 and 0.025 g. respectively of active substance.

G.

α -Methyl-1-naphthylacetic acid diester of N,N'-di-(β -hydroxyethyl)-piperazine dihydrochloride	25

Lactose	150

Corn starch	23

Magnesium stearate	2

Preparation: The active substance, excipients and half of the magnesium stearate are intimately mixed. The homogeneous mixture is then formed into pellets which are granulated. The remaining magnesium stearate is added to the granulate and pressed into convex tablets weighing 200 mg. Each tablet contains 25 mg. of active substance.

EXAMPLE 10

Formulations for the preparation of 1000 vials of 1 cc. volume:	G.

Metamizole	500

α -Methyl-1-naphthylacetic acid diester of N,N'-di-(β -hydroxyethyl)-piperazine dihydrochloride	25

Bidistilled water, q.s. to 1 litre.	

The active substance is added, at room temperature, to the solution obtained by dissolution of the metamizole in about three quarters of the indicated quantity of water and the mixture is stirred until complete dissolution is achieved. The solution thus obtained is made up to the required volume by addition of the remaining water and poured into vials which are then sealed and sterilized. Each vial contains 25 mg. of active substance.

EXAMPLE 11

Formulations for the preparation of 1000 vials of 3 cc. volume:	G.

Metamizole	1250

α -Methyl-1-naphthylacetic acid diester of N,N'-di-(β -hydroxyethyl)-piperazine dihydrochloride	25

Bidistilled water, q.s. to 3 litre.	

Vials are prepared by a method analogous to that described in Example 10. Each vial contains 25 mg. of active substance.

EXAMPLE 12

Formulations for the preparation of 1000 vials of 1 cc. volume:	A	B

	A	B
Nicotinamide	200 g.	200 g.
α -Methyl-1-naphthylacetic acid diester of N,N'-di-(β -hydroxyethyl)-piperazine dihydrochloride	25 g.	50 g.
Bidistilled water, q.s. to	1 l.	1 l.

Vials are prepared from compositions A and B respectively by a method analogous to that described in Example 10. Each vial contains 25 and 50 mg., respectively of active substance.

EXAMPLE 13

Formulations for the preparation of 1000 vials of 2 cc. volume:	G.

Acetamide	300

α -Methyl-1-naphthylacetic acid diester of N,N'-di-(β -hydroxyethyl)-piperazine dihydrochloride	25

Bidistilled water, q.s. to 2 litre.	

Vials are prepared by a method analogous to that described in Example 10. Each vial contains 25 mg. of active substance.

EXAMPLE 14

Formulations for the preparation of 1000 vials of 1 cc. volume:

	G.	
α -Methyl-1-naphthylacetic acid diester of N,N'-di-(β -hydroxyethyl)-piperazine dihydrochloride	25	
3-(2-methoxy-4-propionyl-phenoxy)-1,2-propanediol	100	
N,N'-di-(β -hydroxyethyl)-piperazine	5	
Bidistilled water, q.s. to 1 litre.	10	

The active substance is added to the solution obtained by dissolution of the 3-(2-methoxy-4-propionyl-phenoxy)-1,2-propanediol in about three quarters of the indicated quantity of water. The mixture is stirred until complete dissolution is achieved and then the pH of the solution is adjusted to 4 to 5 by addition of the N,N'-di-(β -hydroxyethyl)-piperazine. The solution is made up to the required volume with the remainder of the water and poured into vials which are then sealed and sterilised. Each vial contains 25 mg. of active substance.

EXAMPLE 15

Formulations for the preparation of 1000 vials of 2 cc. volume:

	G.	
α -Methyl-1-naphthylacetic acid diester of N,N'-di-(β -hydroxyethyl)-piperazine dihydrochloride	25	
3-(2-methoxy-phenoxy)-1,2-propanediol	100	
N,N'-di-(β -hydroxyethyl)-piperazine	5	
Bidistilled water, q.s. to 2 litre.	30	

Vials are prepared by a method analogous to that described in Example 14.

What I claim is:

1. A compound selected from the group consisting of a compound of the formula

wherein R is a member selected from the group consisting of hydrogen and straight-chained alkyl of from 1 to 5 carbon atoms and mono- and di-acid addition salts thereof, the anions of said salts being physiologically acceptable.

2. A compound as claimed in claim 1 wherein R is straight-chained alkyl of from 1 to 3 carbon atoms.

3. A compound as claimed in claim 1 in which R is alkyl of no more than 2 carbon atoms.

20 4. A compound as claimed in claim 1 which is an acid addition salt selected from the group consisting of a hydrochloride, hydrobromide, phosphate, sulphate, methanesulphonate, and methanesulfonate.
